2,447,304

CIRCUIT FOR MINIATURE LAMPS

Carl E. Atkins, Elgin, Ill., assignor to Sun-Kraft, Inc., Chicago, Ill., a corporation of Delaware

Application March 20, 1946, Serial No. 655,700

7 Claims. (Cl. 315—171)

1

This invention relates to a circuit for energizing a gaseous discharge lamp, particularly an ultraviolet or therapeutic lamp. Heretofore a therapeutic or ultraviolet generator has been developed which employs a gaseous discharge lamp of the electrodeless type, which is energized by high frequency oscillating energy. This energy is derived from an electronic tube oscillator circuit. In order to provide an oscillator circuit of such simplicity and compactness that its components could be mounted in a space of restricted area, as for example in the base of a lamp fixture, the oscillating circuit was energized from ordinary low voltage alternating current such as obtained from the house circuit without the use of a power transformer. Such circuits employ a rectifier filter system to provide the direct current voltage for the plate or anode of the oscillator tube. The direct current voltage supply obtained from 115 volt alternating current source is of the order of 85 volts direct current.

It was therefore proposed to energize the oscillator tube directly from alternating current, thereby obtaining peak anode voltage values 1.4 times greater than the R. M. S. of 115 volts. The application of an oscillator of this type to a gaseous discharge lamp, however, has the disadvantage of producing an obnoxious flicker. Since the voltage necessary for starting a discharge in the gaseous discharge tube is greater than the voltage necessary to maintain it, the discharge tube is dark more than fifty per cent of the time. Where the radio frequency peak applied to a gaseous discharge lamp is obtained from an alternating current energized oscillator, erratic operation occurs because the operation is not under steady state conditions.

In accordance with the present invention this disadvantage is overcome by employing two similar oscillators energized in phase opposition from the alternating current line. The gaseous discharge lamp is provided at each end with a pair of electrodes. The output circuits of the oscillators are connected to one of the electrodes of each pair at opposite ends of the gaseous discharge tube. Such an arrangement maintains a discharge through the lamp without flicker.

It is, therefore, an object of this invention to provide an improved electrodeless gaseous discharge tube and circuit therefor whereby the tube may be operated in an improved manner from a standard low voltage alternating current power supply.

It is a further object of the present invention to provide means for supplying to a gaseous dis-

charge tube high frequency oscillating energy derived from an electronic vacuum tube oscillator circuit energized directly from a standard low voltage alternating current power supply such as the ordinary house circuit.

It is a still further object of the present invention to provide an improved high frequency oscillating circuit arranged to have its vacuum tube directly energized from standard low voltage alternating current supplied by the ordinary house circuit without the use of power transformers, rectifiers or filters and which will be capable of energizing a gaseous discharge lamp for therapeutic treatments and other analogous use.

Other and further objects and advantages of the present invention will become apparent from the following description taken in connection with the accompanying drawing wherein the figure is a schematic drawing of a circuit constructed and operated in accordance with the invention.

The present invention as shown in the figure employs an elongated tubular gaseous discharge lamp 2 which is provided at each end with a pair of electrodes. The lamp 2 may be a quartz ultraviolet ray lamp or a fluorescent lamp associated with a high vacuum which is filled with mercury vapor, argon, neon, helium, and krypton or other suitable rare gases and with a small globule of mercury. In the preferred form the lamp 2 is provided with exterior electrodes so that the lamp is commonly referred to as being electrodeless. The lamp 2 at one end is provided with a pair of electrodes 4 and 6 which preferably are in the form of a split ring which also may serve to support or hold the lamp 2 in position in a suitable fixture. At the other end the tube 2 is provided with another pair of split electrodes 8 and 10. High frequency oscillating current is applied to the electrodes at opposite ends of the tube 2 as derived from a pair of vacuum tube oscillators employing vacuum tubes 12 and 14. The vacuum tubes 12 and 14 are each preferably of the indirectly heated cathode type having an anode and a plurality of grids. A suitable type of tube for this purpose is identified as 50L6GT.

The oscillators each employ a tank circuit inductor, the extremities of which are connected to opposite ends of the discharge lamp tube. Thus the one oscillator circuit has a tank circuit inductor 16 having its ends connected to the electrodes 4 and 8 whereas the other circuit has an inductor 18 connected to the electrodes 6 and 10. An intermediate point on the tank inductor 16 is connected to one of the grids of the vacuum tube 12 such as the grid nearest the anode. The in-

termidiate point on the conductor 16 is also connected to one side of the alternating current power supply circuit such as the conductor 20. The other alternating current conductor 22 is connected to the intermediate point on the other oscillator inductor 18 and also to the grid nearest the anode of the vacuum tube 14. The cathode of the vacuum tube 12 is directly connected to the alternating current 22 whereas the cathode of the vacuum tube 14 is connected to the other alternating current conductor 20.

The remaining electrode of the vacuum tube 12 is connected to a grid condenser and leak circuit extending between one end of the tank inductor 16 and the cathode. The grid therefore is connected to the common juncture between the grid condenser 24 and the grid leak 26. Similarly the grid of the vacuum tube 14 is connected to the common juncture of a grid condenser 28 and a grid leak 30 extending between one extremity of the tank inductor 18 and the cathode of the vacuum tube 14. Where the vacuum tubes 12 and 14 are of the type having a 50 volt filament for heating indirectly the cathodes, the two heaters may be connected in series with a small resistor 32 so that the series connected cathode heaters are connected across the alternating current conductors 20 and 22.

From the foregoing it will be seen that the anodes of the vacuum tubes 12 and 14 arranged in two similar oscillator circuits are energized from alternating current in phase opposition. The peak voltage applied to the vacuum tubes 12 and 14 has a value 1.4 times the R. M. S. value of the standard low voltage alternating current power applied to the conductors 20 and 22. Thus the high frequency oscillations developed by the vacuum tubes 12 and 14 during successive half cycles have power values much greater than could be obtained if the alternating current supplied by the conductors 20 and 22 were rectified which would provide a potential of 85 volts. By applying the outputs of the oscillator tank inductors 60 and 18 to opposite ends of the discharge lamp 2, the lamp will not be extinguished during successive half cycles as would be the case if only a single oscillator were employed.

In the preferred form the oscillator circuits employ vacuum tubes of the type identified as 50L6GT having heaters connected in series across the alternating current source with the value of the resistor 32 such that for the normal household voltage 115 volts, the cathode heaters are not subjected to excess voltage. The values of the tank circuit inductor, the grid condenser and the grid resistor are such that the operating frequency is at the selected frequency from among those frequencies assigned by the government for scientific, industrial and medical purposes.

While the circuit as shown has employed vacuum tubes having 50 volt heaters for the cathodes, it, of course, will be apparent that when available other types of tubes having 117 volt filaments may be employed in which case each cathode heater will be directly connected across the alternating current supply line. Similarly other suitable variations are contemplated in the values and circuit arrangement shown without departing from the spirit and scope of the invention as delineated in the following claims.

This invention is hereby claimed as follows:

1. A circuit for energizing a single gaseous discharge tube with associated electrodes comprising a pair of vacuum tube oscillator circuits each including a vacuum tube, a source of alternat-

ing current, means connecting the anodes of said vacuum tubes for energization in phase opposition from said source of alternating current, and means connecting the output of each oscillator circuit to said electrodes of said discharge tube.

2. A circuit for energizing a single gaseous discharge tube from a standard low voltage alternating current source, said tube having an elongated envelope provided with electrodes at the ends thereof, comprising a pair of vacuum tube oscillators energized in phase opposition from a source of alternating current, and means connecting the outputs of said oscillators to said electrodes of said discharge tube to energize said tube during each half cycle of alternating current.

3. A circuit for energizing a gaseous discharge tube by means of electrodes from a standard low voltage alternating current source comprising a pair of vacuum tube oscillators energized in phase opposition from a source of alternating current, each oscillator having a tank circuit inductor, and means connecting said tank circuit inductors to said electrodes of said discharge tube to energize said tube during each half cycle of alternating current.

4. A circuit for energizing a gaseous discharge tube having a pair of electrodes at each end of the tube comprising a pair of vacuum tube oscillator circuits including a vacuum tube, a source of alternating current, means for energizing the anodes of said vacuum tubes in phase opposition from a source of alternating current, and means connecting the output of each oscillator to one of each of said pairs of electrodes.

5. A circuit for energizing a gaseous discharge device having an elongated envelope provided at each end with a pair of external electrodes comprising a pair of vacuum tube oscillator circuits each having a vacuum tube, a source of alternating current, a tank circuit inductor, means for energizing the anodes of said oscillator vacuum tubes in phase opposition from a source of alternating current, and means connecting each tank inductor between one of the electrodes at each of the ends of said gaseous discharge device.

6. A circuit for energizing a gaseous discharge device having an elongated envelope provided with a pair of electrodes at each end thereof from a standard low voltage alternating current source comprising a pair of vacuum tube oscillators each having a vacuum tube provided with a cathode and anode and a plurality of electrodes therebetween, each oscillator circuit having a tank circuit inductor connected to electrodes at opposite ends of said gaseous discharge device, an intermediate point on said inductor being connected to a vacuum tube electrode and to one side of said source of alternating current, one end of said inductor being coupled to the remaining electrode of said vacuum tube, and means directly connecting the anode to the other end of said tank circuit inductor.

7. The combination comprising an elongated gaseous discharge device having a pair of external electrodes at each end, a pair of oscillator circuits each including a tank circuit inductor, a standard low voltage source of alternating current, and a vacuum tube having an indirectly heated cathode, a cathode heater, an anode, and a plurality of electrodes interposed between the cathode and anode, circuit means connecting the cathode heaters of said vacuum tubes in series for energization from said alternating current source, means connecting the cathodes to opposite sides

of said alternating current source, means connecting one electrode of each of said vacuum tubes to opposite sides of said alternating current source and to an intermediate point on the respective tank circuit inductors, means connecting the anodes to one end of each of the respective inductors, means interconnecting the other end of each of the tank circuit inductors to the remaining electrode in each vacuum tube, and means interconnecting said tank circuit inductors 10 each to opposite ends of the external electrodes of said gaseous discharge device.
